HEEL-SHAPING MACHINE

Application filed January 18, 1928. Serial No. 247,507.

Our invention relates to machines for shaping wood heels and it has for its object to provide an improved and efficient machine of this class.

At present most women's shoes are made with wood heels and a popular and extensively used style is known as the Louis heel. This particular kind of heel is made with a shank or lip at the top of its breast which is very thin and transversely arcuate or curved. Originally this shank was shaped or molded upon its under side manually by a workman holding the heel with two hands and wiping the shank against a rapidly rotating sand 10 per wheel. This method is still employed to a considerable extent. Obviously exact or even substantial uniformity in all heels was impossible by this method as the degree of accuracy with which the shank was shaped depended altogether upon the skill of the workman.

Machines have been produced for shaping the breasts and shanks of wood heels, two machines being employed, one for shaping the breasts and the other for shaping the shanks. In all instances with which we are familiar, the shank shaping was effected by presenting the heel to a rapidly rotating cutter head, usually an internal cutter head, whose blades travelled completely across the shank of the heel, starting at one side of the breast of the heel and passing from the latter at the opposite side thereof. The result of this mode of operation was to produce a clean sharp corner at the side of the heel breast which the cutter first engaged, while at the opposite side of the breast the corner would be left rough and feathered, requiring manual touching up or trimming to remove the feather edge. A further objection was that the cutter would often chip or split the heel, particularly the thin shank thereof, adjacent the side at which the cutter departed from the work, thus destroying a large percentage of the heels operated upon.

In the manufacture of wood heels the shank shaping is almost invariably the last of several separately performed shaping operations necessary to convert a wood blank 50 into a completely shaped heel. One of the

several operations referred to is the concaving of the top of the heel to adapt it to fit the convex heel portion of the sole of the shoe, and the depression formed by this concaving operation extends into the shank, so that 55 when the last operation of breasting or shank shaping is performed the exterior or under side of this shank is made transversely convex, the lip being reduced so that it is very thin and frail particularly at its forward end. 60 It will, therefore, be clear that the problem of shaping the exterior or under side of the shank without destruction of the heel and without production of a feather edge as described is important. 65

The purpose of the invention is to provide an efficient machine for accurately and rapidly shaping the breasts and under faces of shanks of wood heels without production of split or feathered edges. 70

The character of the invention may be best understood by reference to the following description of one good form thereof shown in the accompanying drawings, wherein:

Figure 1 is a front elevation of the upper 75 portion of the heel shaping machine;

Fig. 2 is a front elevation of the machine with some of the mechanism at the top thereof removed;

Fig. 3 is a detail hereinafter described; 80

Fig. 4 is a side elevation of the machine showing parts broken away and parts of the work holder removed;

Fig. 5 is a side elevation of the mechanism shown in Fig. 1, as viewed from the left; 85

Fig. 6 is a front elevation of one of the cutters;

Fig. 7 is a side elevation of a wood heel block to be shaped;

Fig. 8 is a perspective view of the heel 90 after being shaped; and

Fig. 9 is a plan view of the work holder.

The machine shown herein as one good form of the invention has two rotary cutters supported in a predetermined spaced relation 95 and a movable work holder which grips and firmly holds the work while being operated upon by said cutters. This work holder is reciprocated to shift it first into cooperative relationship with one rotary cutter and then 100

the other, and it is also oscillated in timed relation with its reciprocating movement so as to swing the heel sidewise into engagement with the cutters successively. Thus the block 5 is first presented sidewise to one of the rotary cutters which partially shapes the breast and under face of the shank by cutter strokes directed inward from one side of the heel, and then the block is presented sidewise to the 10 other rotary cutter which completes the shaping thereof by cutter strokes directed inward from the opposite side of the heel. While the construction and mode of operation just referred to is a characterizing and distinguishing 15 feature of our improved machine in its best form whereby the production of the feather edge referred to is avoided, yet the fundamental idea involved in the same is the provision of the two rotary cutters which operate in succession upon the block of the heel 20 from opposite sides thereof, one entering into engagement with the block at one side of the latter and partially traversing the breast and shank and the other entering into engagement 25 with the block at the opposite side thereof and completing the breast and shank shaping operation; the heel and heel holder being oscillated in one direction to cause the first cutter to perform its work and in the opposite 30 direction to cause the second cutter to perform its work, thus producing a transversely concave breast and a convex exterior surface on the shank which may be approximately parallel with the surface of the concave top of the heel. 35

Referring to the drawings, 1 and 2 designate two continuously rotating cutter heads, the former rotating in a left hand direction as is indicated by an arrow in Fig. 1 and the latter rotating in a right hand direction as is also indicated by an arrow in Fig. 1. The cutter head 1 is fast on a shaft 3 journaled in bearings 4 on the frame 5 of the machine, and the cutter head 2 is fast on a shaft 6 40 journaled in bearings 7 on said frame. At the bottom of the frame is a platform 8 on which is mounted an electric motor 9 whose armature shaft 10 carries two pulleys 11 and 12, Figs. 2 and 4, pulley 11 being connected by a crossed belt 13 with a pulley 14 fast on shaft 3 of cutter head 1, and the pulley 12 is connected by a straight belt 15 with a pulley 16 fast on shaft 6 of cutter head 2. Thus the two cutter heads are driven from the motor 50 in opposite directions.

The work holder of the machine is indicated generally at 17 and includes a fixed, but angularly adjustable jaw 18, Figs. 1 and 9, and a movable jaw 19 between which a wood heel H is clamped on the work holder. The heel H is engaged by a breast-engaging gauge 20 and a side gauge 21, Figs. 4, 5 and 9.

The work holder 17 is mounted upon a slide or carriage 22 resting on ways 23 and is held 65 down thereon by gib 24 on the carriage. A

link 25 is connected to the carriage and top of an upstanding lever 26 fulcrumed at 27 on frame 5. A cam roll 28 on the lever engages a cam 29 (Figs. 2 and 4) fast on the main shaft 30 of the machine. To rotate the 70 shaft a gear 31 thereon meshes with a pinion 32 fast on one end of a transverse, inclined shaft 33 journaled in bearings on the frame of the machine. At its opposite end this shaft carries a worm wheel 34 driven by a worm 75 35 fast on a countershaft 36 journaled in bearings on the frame. This countershaft carries a pulley 37 connected by a belt 38 with a pulley 39 fast on the armature shaft 10 of the motor. 80

The gear 31 is loosely mounted on shaft 30, but is held against endwise movement relatively thereto. A one-revolution-and-stop mechanism 40 is provided on shaft 30 and cooperates with the hub of gear 31. This 85 mechanism is of usual construction, and therefore it is unnecessary to show and describe the same in detail herein. A revolution of the shaft 30 is initiated by pressure on a foot treadle 41 normally held up by a spring (not 90 shown). After the shaft 30 makes one revolution the mechanism automatically is disconnected from the hub of gear 31 and another revolution of the latter can not be occasioned until after treadle 41 has moved upward to its normal elevated position. Each 95 revolution of the shaft 30 reciprocates the lever 26 once, starting from a position of rest which is at the extreme of its movement toward the left in Figs. 1 and 2. Through the 100 connections just described the carriage 22, the work holder 17 and the heel H carried by the latter, are reciprocated on the ways 23 to shift the work holder 17 out of cooperative position with relation to cutter 1 and into cooperative 105 relation with the other cutter 2, followed by return of the work holder 17 into cooperative relationship with the cutter 1.

When opposite each cutter head the work holder 17 is oscillated by mechanism including a pinion 43 (Fig. 5) fast upon the lower end of a vertical spindle 44 on the carriage and carrying the work holder. Pinion 43 is engaged by a rack 45 connected by a link 46 with the top of an upstanding lever 47 (Fig. 115 2) fulcrumed at its lower end at 27 on the frame. This lever 47 carries a roll 48 engaged by a cam 49 fast on shaft 30. The two cams 29 and 49 (Fig. 2) receive a revolution from shaft 30 and reciprocate the two levers 110 26 and 47. The lever 47 normally occupies a position at the limit of its movement toward the left in Figs. 1 and 2.

The breast-engaging and heel-positioning gauge 20 is held in operative position by a cam 50 (Figs. 3 and 4) fast on shaft 30 and cooperating with a roll 51 mounted upon the lower end portion of an upstanding connecting rod 52 adjacent the back of the machine. The upper end of this rod is pivotally con- 125

nected with one arm of a bell-crank lever 53 fulcrumed at 54 on the frame, and the other arm of said lever carries an adjustable abutment screw 55 engaging the rear end of a 5 push rod 56 slideable longitudinally in bearings on the frame of the machine. The forward end of said rod engages the gauge member 20 which is yieldingly held against said end by a spring 57, Figs. 5 and 9. The cam 10 50 moves the gauge 20 down into operative position just as the shaft 30 completes each revolution and at the start of each revolution said cam 50 permits the spring 57 to raise the gauge 20 into an elevated position where 15 it is out of the path of the heel, and where it remains until the revolution of the shaft 30 is nearly completed.

The heel positioning gauge 20 is pivotally supported by a pintle 58 (Figs. 5 and 9) having threaded engagement with a lug 59 on the machine frame. The gauge can be adjusted laterally as may be required for different shapes or styles of heels by rotative adjustment of the pintle.

25 The work holder 17 (Figs. 1 and 9) includes a base frame comprising a pair of parallel side bars 60 having standing cheeks 60^a connected by a cross bar 60^b having a hole receiving the shank of a screw 61 provided at its outer end with a handle, said screw being confined against movement longitudinally relatively to the cross bar 60^b. The screw 61 is threaded into a bore in a block 62 fitting and adapted to slide between the walls 60^a. At 35 the top of the block are outstanding flanges resting upon the top edges of the cheeks 60^a. The block has a vertical hole receiving the upper end portion of the spindle 44 to which it is locked against rotative displacement 40 thereon by a key 63 (Fig. 4). The block and the two bars 60 rest upon and are clamped down against a capstan nut 64 by a nut 65 threaded to the upper end of spindle 44. The capstan nut is threaded to the intermediate 45 threaded portion 67 of spindle 44. This construction permits accurate vertical positioning of the heel supporting parts of the work holder with respect to the rotary cutters 1 and 2, and the screw 61 permits accurate positioning of said parts laterally with respect to the cutters 1 and 2. These adjustments may be 50 made when shifting from one style or shape of heel to another.

55 The cheeks 60^a have slots 68 receiving clamping screws 69 threaded into bores in the block 62. When these screws are set up they clamp the block and cheeks together in their adjusted positions.

60 The fixed heel-engaging and clamping jaw 18 has its lower end pivotally mounted on a pin 70 (Fig. 1) extending between and carried by the side bars 60. Pivotally connected to the jaw are a pair of slotted links 71 adapted to be rigidly clamped to the cheeks by

screws 72, thereby to hold the jaw in different positions of angular adjustment.

The jaw 19 is set into a socket 19^a (Fig. 5) on a cross-head 73 (Figs. 1 and 9), and is held by a screw 74 extending through a slot 75 70 (Fig. 5) in the cross-head, and threaded into a bore in jaw 19. Secured to the cross-head 73 are rods 76 slideably mounted in holes extending longitudinally through the side bars 60. The ends of the rods 76 opposite to the 75 cross-head are threaded to receive nuts 77 in recesses at the opposite ends of an abutment bar 78 (Figs. 1 and 9) carrying a roller 79 cooperating with the cam hub of a clamp-operating lever 80 fulcrumed at 81 between 80 the ends of the side bar 60. A pair of springs 82 are connected with the abutment bar 78 and with the bars 60 and urge the jaw 19 in heel unclamping direction toward the left (Figs. 1 and 9).

85 When the free end of the clamping lever 80 is thrown upward its cam hub permits the springs 82 to act through abutment bar 78, nuts 77, slide rods 76 and cross-head 73, and shift the jaw 19 away from the jaw 18 to 90 allow insertion of a heel between the jaws or removal of the heel therefrom. When the free end of clamping lever 80 is thrown downward until it rests upon the abutment bar 78, its cam hub acts through said abutment bar, nuts, rods, and cross-head, to cause the jaw 19 to clamp a heel rigidly in position between the jaws. The operator may use one hand to place the heel in position against jaw 18, gauge 20 and gauge 21, and he may use his other hand to throw the lever 80 down and clamp the heel in place.

95 Secured to the under side of the opposite ends of the carriage ways 23 (Fig. 5) by screws 83 are four lug plates 85 projecting into grooves 86 extending longitudinally in the outer sides of two arms 5^a constituting part of the frame of the machine. These lug plates 85 lock the ways 23 to the arms and allow them to be adjusted, together with the work holder 17, toward and from the cutters as may be required by the size or style of heel to be operated upon, and to compensate for wear or grinding of the cutters. To effect this adjustment a screw 87 is provided having a shank portion rotatably mounted in a bore in a cross bar 88 which is part of the machine frame. The screw is confined against movement in the direction of the length thereof. The inner end portion of the screw is threaded into a bore in one of the ways 23 and at its outer end is a handle 89 by means of which it may be adjusted.

When a wood heel has been prepared for the shank shaping operation it has the form shown in full lines in Figs. 7 and 8, in which 90 designates the shank of the heel and 91 the concaved top thereof. After the heel has been operated upon by the machine, the shank portion thereof has been reduced from the

full line form shown in Figs. 7 and 8 an amount indicated by the dotted lines in Fig. 8.

The boss 22^a of the carriage 22 has rigidly coupled to its lower end a yoke 92 that embraces and holds in cooperative relationship the rack 45 and pinion 43, said yoke providing a guide for the rack when the latter is moved endwise relatively to the pinion 43 by lever 47. This yoke is held interlocked with the lower end of boss 22^a by means of a nut 93 on the lower threaded portion of spindle 44.

The coupled shank lip on the heel is very thin and frail and since the parts of the machine are so adjusted that the heel H is gripped forcibly by the clamping jaws 18 and 19, it is desirable to provide, as herein shown, a supporting post 100, (Fig. 9), which may be a screw adjustably mounted in the upper end portion of the clamping jaw 18 and engaging the concaved top side of the heel to support the same against the pressure of the clamping jaws and the thrust of the cutter.

The side gauge 21 is fastened rigidly to the fixed jaw 18 by a clamping screw 101 (Fig. 5) extending through a slot in gauge 21, its inner end being threaded into a bore in said jaw. The gauge 21 is made with a laterally extending ear swivelled on the rear end of a stem 102 (Fig. 9) threaded into a hole in said jaw. At its forward end the stem 102 is provided with a handle 103 by means of which the stem can be rotated to adjust gauge 21 after loosening clamping screw 101.

In use, the operator places a heel block H (Fig. 7) in the machine with its top resting against the jaw 18, its front face resting against the gauge 20 and a side resting against the gauge 21. While holding the heel in this position the operator throws the clamping lever 80 down thereby causing the jaws 18 and 19 to grip the heel. He then depresses the foot treadle 41 which causes the shaft 30 to make one revolution and stop. The gauge 20 is thrown up out of the way immediately at the start of cam shaft rotation, and during the first half of this rotation the two levers 26 and 47 move together toward the right (Figs. 1 and 9), and the work holder is shifted from a position where the axis of spindle 44 intersects the extended axis of the shaft 3, to a position where the axis of the spindle intersects the extended axis of the shaft 6. During the last half of the cam shaft rotation the work holder is shifted back to its first position again. Thus the work holder is shifted back and forth from one cutter to the other. During the first half of the cam shaft rotation, and while the work holder is traveling from cutter 1 to cutter 2, the upper end of the lever 47 is caused to travel faster than the upper end of the lever 26, thereby causing the heel to be swung sidewise in a clockwise direction (Fig. 9), whereby to given point on the front face of the heel near the tread

end thereof will travel in the curved path indicated by the arrows that are pointed toward cutter 2. During the last half of the cam shaft rotation the work holder is shifted from cutter 2 back to cutter 1 and during this movement of the holder, and while it is travelling back to cutter 1, the lever 47 is caused to lag behind the lever 26, thereby continuing the rotative adjustment of spindle 44 so that at the instant that the holder is returned to its first position opposite cutter 1 the heel occupies approximately the dot-and-dash position indicated at g. While the holder is moving from cutter 2 to cutter 1 the aforementioned point on the front face of the heel will travel approximately the sinuous path indicated by the arrows that are pointed toward cutter 1 and which are between the position of the heel indicated at e and the position indicated at g. At the moment that the heel reaches the position indicated at g the lever 26 completes its movement toward the left (Figs. 1 and 2), which occurs before lever 47 has returned to its starting position. Therefore, the continued movement of lever 47 will rotate the work holder on the axis of spindle 44 and thereby swing the heel from the position indicated at g around to the position from which it started, indicated at a. During this swing of the heel the point above referred to would traverse the path indicated by the arrows which are concentric with the axis of spindle 44 in Fig. 9.

During the travel of the work holder toward the right the axis of spindle 44 reaches a position where it intersects the extended axis of shaft 6 before the heel, shown as approaching cutter 2 at b, c and d, is engaged by said cutter. After the work holder reaches this position where the axes intersect, movement of lever 26 toward the right ceases while the movement of the lever 47 toward the right continues thereby swinging the heel around the axis of the spindle 44 into the position indicated at e during which time the cutter 2 traverses and operates upon only one side portion of the shank lip. That is, the movement of lever 47 does not continue far enough to swing the heel past cutter 2. When the heel is later swung from the position indicated at g around the axis of spindle 44 to the position indicated at a, the cutter 1 completes the shaping of the shank lip. It will be clear that both cutters operate upon the heel by cutting strokes which are directed inwardly from the sides of the breast so that chipping or splitting of the heel is avoided and a clean, sharp corner free of feather is produced at each side of the breast.

It will be understood that the invention is not limited to the specific embodiment shown, and that various deviations may be made therefrom without departing from the spirit and scope of the appended claims.

What is claimed is:

1. A machine for shaping front concave breasts, and under convex faces of shanks of wood heels comprising, in combination, a pair of rotary cutters, a heel block holder, and means to move the holder and heel block relatively to the rotary cutters to cause the cutters successively to shape portions of the concave breast and under convex face of the heel shank with cuts commencing at opposite sides of the heel block and directed inward therefrom.

2. A machine for shaping breasts and shanks of wood heels comprising, in combination, a pair of rotary cutters, a heel block holder, and means to impart to the heel holder and a heel block reciprocatory and oscillatory movements to cause the cutters successively to shape portions of the breast and under face of the heel block shank with cuts commencing at opposite sides of the heel and directed inward therefrom.

3. A machine for shaping breasts and shanks of wood heels comprising, in combination, a pair of spaced rotary cutters, a heel block holder, and means for moving the holder and a heel block to present the heel to said cutters and having provision for imparting partial rotative movements to the holder when at said cutters, that one cutter may partially shape the breast and under face of the heel shank, and the other cutter may complete shaping of said breast and shank.

4. A machine for shaping breast and shanks of wood heels comprising, in combination, a pair of spaced rotary cutters, means to rotate said cutters in opposite directions, a heel block holder, means to rock the holder and a heel block thereon relatively to one of the cutters, that the cutter blades may make strokes inward along the breast and under face of the heel shank from one side of the heel shank, said means having provision to rock the holder and heel relatively to the other cutter, that the blades thereof may make strokes directed inward along said breast and shank face from the opposite side of the heel.

5. A machine for shaping breasts and shanks of wood heels comprising, in combination, a support, a pair of rotary cutters mounted on the support, means to rotate the cutters in opposite directions, a carriage on the support, a heel block holder on the carriage, and means to reciprocate the carriage and the holder to present a heel successively to said cutters to shape the breast and under face of the heel shank.

6. A machine for shaping breasts and shanks of wood heels comprising, in combination, a support, a pair of rotary cutters mounted on the support, means to rotate said cutters, a carriage, a spindle on the carriage, a heel block holder mounted on the spindle, means to reciprocate the carriage to carry a heel block from one of the cutters to the other

70 cutter, and means to impart rotative movement to the spindle and holder, thereby to rock the heel block relatively to the cutters, that they may shape portions of the breast and under face of the heel shank.

7. A machine for shaping breasts and shanks of wood heels comprising, in combination, a pair of rotary cutters, a heel block holder movable to a heel loading and discharge station, means to feed the holder from one of the cutters to the other cutter, and means to impart rotative movement to the holder when at said cutters, that each may shape a portion of the breast and under curved face of the heel shank.

75 80 85 90 95 100 105 110 115 120 125

8. A machine for shaping breasts and shanks of wood heels comprising, in combination, a pair of rotary cutters, a heel block holder having a pair of jaws for gripping a heel block between them, means for relatively moving said jaws to clamp and release the block, means to feed the holder from one of the cutters to the other cutter, and means to rock the holder when at said cutters, that the latter may shape the breast and convex under face of the heel shank.

9. A machine for shaping breasts and shanks of wood heels comprising, in combination, a pair of rotary cutters, a heel block holder having a pair of jaws for gripping a heel block between them, a gauge for engagement with the front face of the block, means for moving said gauge to and from active position, and means for moving the holder to cause the cutters successively to shape portions of the breast and under face of the heel shank.

10. A machine for shaping breasts and shanks of wood heels comprising, in combination, a pair of rotary cutters, a heel holder having jaws for gripping a heel between them, a gauge for engaging the front face of the block, actuating means for automatically moving the gauge to and from active position, and means for successively presenting the block to the cutters in a path to cause them to shape portions of the under face of the heel shank, said gauge actuating means having provision for moving the gauge away from the heel prior to movement of the holder.

11. A machine for shaping breasts and shanks of wood heels comprising, in combination, a pair of rotary cutters, a heel block holder having a pair of jaws for gripping a heel block between them, a gauge on the holder for engagement with a side of the block, a gauge for engagement with the breast of the heel, and means for moving the holder to present the heel block successively to the cutters, that they may shape the under face of the heel shank.

12. A machine for shaping breasts and shanks of wood heels comprising, in combination, a pair of rotary cutters, a heel block

holder having a pair of jaws for gripping a heel block between them, a gauge on the holder for engagement with a side of the heel, a gauge for engagement with the front face 5 of the block, means for adjusting said gauges to suit heels of different styles or sizes, and means for moving the holder relatively to the cutters.

13. A machine for shaping breasts and 10 shanks of wood heels comprising, in combination, a pair of rotary cutters, a heel block holder having a pair of jaws for gripping a heel block between them, a gauge on the holder for engagement with a side of the 15 block, a gauge for engagement with the front face of the block, means for adjusting said jaws and gauges to suit heels of different styles or sizes, and means for moving the holder relatively to the cutters.

20 14. A machine for shaping breasts and shanks of wood heels comprising, in combination, a pair of rotary cutters, a heel block holder having means for gripping a heel, means for moving the holder successively to 25 said cutters, means for rocking the holder when at said cutters to cause the latter to shape portions of the breasts and under face of a heel shank, and means to adjust the holder relatively to the cutters to suit heels 30 of different styles or sizes.

15. A machine for shaping breasts and shanks of wood heels comprising, in combination, a pair of rotary cutters, a heel block holder, a spindle, a capstan nut threaded on 35 the spindle for supporting the holder and adjustable to move the holder relatively to the cutters to suit heels of different styles or sizes, and means successively to present the holder and a heel block thereon to the cutters, 40 that they may shape portions of the breast and under face of the heel shank.

16. A machine for shaping breasts and shanks of wood heels comprising, in combination, a pair of rotary cutters, a carriage, a 45 heel block holder on the carriage, means to reciprocate the carriage and holder transversely to the axes of the cutters, and means to oscillate the holder and a heel block in opposite directions when at said cutters, there- 50 by to cause the latter to shape portions of the breast and under convex face of the shank of the heel.

17. A machine for shaping breasts and shanks of wood heels comprising, in combina- 55 tion, a pair of rotary cutters, a carriage, a heel block holder on the carriage, means including a cam for reciprocating the carriage and holder transversely to the axes of the cutters, thereby successively to present a heel 60 block on the holder to said cutters, and means including a cam for imparting oscillatory movements to the holder and block when at said cutters, thereby to cause the latter to shape portions of the breast and under face 65 of the heel shank.

18. A machine for shaping breasts and shanks of wood heels comprising, in combination, a pair of rotary cutters, a heel block holder, a shaft, cams fast on said shaft, means operated by one of the cams for imparting re- 70 ciprocatory movements to the holder, means operated by the other cam for imparting os- cillatory movements to the holder, and means for rotating said shaft including a one-revo- lution-and-stop-mechanism.

19. A machine for shaping breasts and shanks of wood heels comprising, in combination, a pair of rotary cutters, a heel block holder, a shaft, cams fast on said shaft, means operated by one of the cams for imparting re- 80 ciprocatory movements to the holder, means operated by the other cam for imparting os- cillatory movements to the holder, means for rotating said shaft including a one-revo- lution-and-stop-mechanism, and a treadle oper- 85 able to initiate said revolution.

20. A machine for shaping breasts and shanks of wood heels comprising, in combination, a pair of rotary cutters, a carriage, a spindle on the carriage, a heel block holder 90 on the spindle, a cam, a lever rocked by the cam, and a link connected to the lever and carriage, that the cam may reciprocate the carriage, a second cam, a lever rocked by the latter, a rack connected to the latter lever, and 95 a gear on the spindle meshing with the rack, that the second cam may impart oscillatory movements to the spindle.
